AUTOMOBILE DOOR WINDOW MECHANISM

Daniel L. Chandler, Salem, Mass., assignor to
 The Aresee Company, Inc., Swampscott, Mass.,
 a corporation

Application January 25, 1944, Serial No. 519,599

5 Claims. (Cl. 268—19)

My present invention relates to automobile windows and more particularly to electrically operated automobile door windows.

The principal object of my invention is an improved automobile door window of the electrically operated type;

Another object is an improved automobile window and ventilator operator operated from a single control lever;

Another object is an improved electrical operator for automobile windows and the like having a common driving member which operates either the main sliding window pane or the swinging ventilator, as the case may be;

Still another object is an improved electrically operated automobile door window in which provision has been made to break the seal between the sliding window sash and the door frame occasioned by freezing temperatures, or in other words, starting a frozen-in window pane, and

Numerous other objects will appear as the description of the construction and operation of my invention progresses.

In the drawings illustrating the preferred embodiment of my invention:

Fig. 1 is a diagram showing the side elevation of an automobile door, portions of which have been broken out for convenience sake, and showing the main sliding sash and general position of the electrically operated mechanism indicated in broken lines for the purpose of broadly indicating the general position and connecting members of my invention as they are located in the said door;

Fig. 2 is a plan view of the unit which is mounted in the lower portion of the automobile door, as indicated in Fig. 1, portions of one end of the unit being broken off for convenience;

Fig. 3 is a side elevation of Fig. 2, portions of the same end being broken off, as in Fig. 2 for convenience;

Fig. 4 is a side elevation of Fig. 3, as viewed from the opposite side from that shown in Fig. 3;

Fig. 5 is an enlarged fragmentary side elevation of the upper end of the rack member which connects to the lower edge of the window frame particularly showing the upper cam member which operates the electrical switch and stops the mechanism when the window has reached its lowermost limit of travel and the elongated slot which provides a lost motion period which acts to break the seal of a frozen window, as mentioned above in the objectives;

Fig. 6 is a cross-section taken on the line 6—6 of Fig. 2, the scale being practically full size to

better show the detail of the internal mechanism as it appears just inside the front side of the casing;

Fig. 7 is a cross-section taken on the line 7—7 of Fig. 3 also shown in full scale, portions of which are shown in plan elevation;

Fig. 8 is a fragmentary cross-section taken on the line 8—8 of Fig. 6 particularly showing certain parts of the mechanism which are controlled from the switch-operating lever;

Fig. 9 is another cross-section taken on the line 9—9 of Fig. 6 also showing the mechanism from a higher plane being controlled from the switch-operating lever;

Fig. 10 is a fragmentary plan elevation of the slide member shown in the uppermost portion of Fig. 6 which operates to cut out the electrical switch and stop the electric motor when the swinging ventilator window reaches its limit of travel;

Fig. 11 is a side elevation of the switch block removed from the casing;

Fig. 12 is a front view of the switch shown at Fig. 11, the front cover plate having been removed to better show the interior;

Fig. 13 is a side elevation of the switch, as viewed from the opposite side to Fig. 11;

Fig. 14 is an expanded view of Fig. 12, the central switch member having been removed and the two sides shown at Fig. 11 having been cut off and turned to the right and left-hand sides to better show the inside of the back portion and the two sides;

Fig. 15 is a side elevation of the switch lever 35 which makes contact with the inside surface of the side portion shown at the left-hand side of Fig. 14;

Fig. 16 is the opposite side of the switch lever shown in Fig. 15 showing the switch contact portion which engages with the inside surface of the side portion shown at the right-hand side of Fig. 14;

Fig. 17 is a developed view of the switch contact members which are attached to the lever 45 member, shown in Figs. 12, 15 and 16;

Fig. 18 is a cross-section taken on the line 18—18 of Fig. 7 showing the reversible window and ventilator driving unit in elevation;

Fig. 19 is a side elevation of Fig. 18 showing 50 the unit illustrated in Fig. 18 from a point inside the frame in which it is supported and having the pinion member removed;

Fig. 20 is a similar elevation to Fig. 19 but with the top disc shown in Fig. 19 removed;

Fig. 21 is another view similar to Fig. 20 but

with the cover plate and slide shown in Fig. 20 removed;

Fig. 22 is another strip-down elevation similar to Fig. 21 with the dog member shown in Fig. 22 being removed;

Fig. 23 is another strip-down elevation similar to Fig. 22 but having the dog-breaking ring removed;

Fig. 24 is still another strip-down elevation similar to Fig. 23 but having the notched dog member removed;

Fig. 25 is a final strip-down elevation having all the parts removed down to the bare worm wheel;

Fig. 26 is a transverse cross-section taken on the line 26—26 of Fig. 18;

Fig. 27 is a bottom plan view of the dog member shown in Fig. 21;

Fig. 28 is a plan view of the four-way control lever which is mounted in the upper portion of the automobile door and from which the electrical switch is operated from the unit mounted in the lower door portion;

Fig. 29 is a front elevation of Fig. 28, the rod which connects with the lower unit being broken off;

Fig. 30 is a cross-section taken on the line 30—30 of Fig. 29;

Fig. 31 is a cross-section taken on the line 31—31 of Fig. 29, and

Fig. 32 is a wiring diagram of the electrical circuit which is used with the switch, shown in Figs. 11 to 17 inclusive, and the reversible electric motor which is mounted in the main unit and drives the worm wheel illustrated in Fig. 25 and various other views throughout the drawings.

Referring more specifically to the drawings illustrating the preferred embodiment of my invention, it should be noted that Fig. 1, which is more or less diagrammatical in form, shows an automobile door, as generally indicated at 10 having a main vertical sliding sash 11 and a swinging ventilator window 12. The sliding sash 11 is connected to the main unit 13 which is mounted in the lower portion of the door by means of a rack member 14 which is connected to the lower frame 15 of said sash. This rack raises and lowers the sash 11 from mechanism which will be fully described later and which is contained with the unit 13. The ventilator 12 is swung in alternate directions, as when opening and closing same, by means of the rod 16 which is also connected with the unit 13. Also located in the door but not shown in Fig. 1, is the control lever, better shown in Figs. 28 to 31, which also connects with the unit 13 for the purpose of operating the electrical switch elements.

The heart of the mechanism is located in the unit 13 as illustrated in Figs. 18 to 27, and Figs. 6 to 10 inclusive illustrate the connection between the mechanism shown in Figs. 18 to 27 and the apparatus which operates the switch mechanism which is positioned by means of the control apparatus shown in Figs. 28 to 31 inclusive.

The complete driving mechanism and switch control mechanism is contained in the unit 13 in which is mounted a reversible electric motor 17 the motor drive shaft 18 of which is coupled at 19 to a worm gear 20 which engages a worm wheel 21 transversely mounted in the unit 13. The sides of the unit 13 are indicated by the numeral 22 which indicates the front side, as viewed from the interior of the automobile, and 23, as viewed from the opposite side of the mechanism. The window sash 11 is raised and lowered by means

of the rack 14 which is engaged with the pinion 24 when the pinion 24 rotates in a right or left-hand direction, as the case may be. In a similar manner the ventilator window 12 will swing to one side or the other, as the case may be, when the rack 25 is moved in the corresponding direction. By an inspection of Fig. 4 it will be observed that a second pinion 26 is engaged with the teeth of the rack member 25, the major axis of the pinion 26 and the pinion 24 being the same. It will thus be seen that when the pinion 26 rotates, the rack 25 will move in a horizontal direction, and due to the fact that the rack 25 is engaged with the gear 27 which is directly connected with the pinion 28 which is engaged with the gear 29 which is directly connected with the rod 16, the ventilator window 12 will swing to the right or left, as the case may be when the rack 25 is moved.

The unit disclosed in Figs. 18 to 27 inclusive comprises a multiple driving mechanism which operates the pinions 24 and 26, said pinions being independently operated clockwise or counter-clockwise by means of the worm wheel 21 which operates clockwise or counter-clockwise from the electric motor 17. In other words, the pinion 24 which engages the rack 14 will raise or lower the sash 11 by means of the reversible motor 17, and in a similar manner, the pinion 26 will operate the horizontal rack to the right or left, as the case may be, from the said motor 17. Both pinions 24 and 26 are driven forward or reverse by means of the worm wheel 21 only if the mechanism adjacent the pinion in question and between the said pinion and the worm wheel 21 is in a driving position; otherwise either of said pinions will be disengaged from the worm wheel 21. As will be noted, as the description progresses, both of the pinions 24 and 26 cannot be driven from the worm wheel 21 at the same time; therefore it will be observed that the apparatus mounted on each side of the worm wheel 21 constitutes a friction clutch mechanism and the entire unit, as set forth in Figs. 18 to 27, constitutes a multiple clutch.

In the description of the apparatus, Figs. 18 to 27 illustrate and describe one side of the unit as separated by the worm wheel 21, the opposite side being a duplicate and operating in an identical manner excepting as controlled by other apparatus. Figs. 19 to 25 inclusive illustrate the internal mechanism of one side of the multiple clutch in a successive elimination of parts as removed from the outer side adjacent the pinion 24 inwardly to the face of the worm wheel 21. In Fig. 19 the first disc 30 is provided with a plurality of slots 31 and segment members 32. The disc 30 is freely journaled about the shank portion 33 of the pinion 24, see Fig. 26; Fig. 20 shows the mechanism directly under the disc 30. The portion indicated at 34 is provided with tapped holes 35 and 36 and adapted to receive the screws 35a and 36a, shown in Fig. 19. The screw 35a holds a block member 37, see Fig. 19, in which is secured the circular spring member 38, and a cut-out portion 39 permits the disc 30 to rotate a short distance to the right or left of the block member 37. On the opposite side of the unit is located the spring stop member 40 which limits the movement of the free ends of the said spring. Another slot 41, similar to slot 39, is provided to allow the disc 30 to rotate a short distance to the right or left of the screw 36a. It will thus be seen that the disc 30 may be rotated to the right or left on the shank 33 of the pinion member 24 within the limits of the

slots 39 and 41; and inasmuch as the spring 38 is secured in the block 37 which is in turn fixed on the member 34, the disc 30 will always return to a neutral position, as shown in Fig. 19, when not otherwise held from so doing. In the same disc 30 there is another opening comprising an oblique angled slot 42 through which projects a pin 43; see Fig. 20, which is attached to a slide member 44 slidably located in slide-way 45 in the member 34. The slot 42 acts as a cam track so that when the disc 30 is rotated to the right or left around the pinion 24, the pin 43 will move the slide member to the left in the slideway 45. Also located on the periphery of the member 34 is a plurality of slots 46, also shown in dotted lines in Fig. 19. It will thus be seen that when the disc 30 is rotated to the right or left, these slots 46 will be exposed such that a pawl member attached to the unit 13, as will be described later, could be engaged in the slots 46 thereby locking the member 34 from turning further. By a further inspection of Figs. 20 and 26, it will be observed that the member 34 is provided with a square hole 47 and that the corresponding portion 33 of the shank of the pinion 24 is squared to fit this square hole; therefore it follows that when the member 34 is locked against rotation, the same is true regarding the pinion 24. In Fig. 21, the member 34 has been removed to disclose the structure directly beneath, and which includes a disc 48 on which is mounted and a part thereof an open ring portion 49 provided with tapped screw holes 50 which are adapted to receive the screws 51 which secure the member 34 thereto. It will thus be seen that when the disc 48 is rotated to the right or left, the member 34 will also rotate and the pinion 24 will move likewise. In Fig. 23 I have shown a notched member 52 which is secured to the worm wheel 21 by means of the screws 53 engaging in the tapped holes 54 located in the worm wheel 21. Therefore, due to the fact that the member 52 is positively secured to the worm wheel 21, it follows that when the worm wheel 21 moves, the member 52 must move also. It will thus be seen that in order to effect a drive between the worm wheel 21 and the pinion 24 the member 52 must be locked with the member 34 having the square hole 47 engaging with the squared portion 33 of the pinion 24. To produce this condition, I have devised the following intermediate structure. Between the two open ends of the portion 49 on the disc 48 I have pivoted the dog member shown in Fig. 27 and Fig. 21, Fig. 27 being a reverse side view from that shown in Fig. 21 in which it will be observed that the dog member 55 is provided with trunnion portions 56 located on either side of the dog member 55, the lower side, as viewed in Fig. 22, being pivoted in the hole 57 located in the disc 48 and the upper side of which is pivoted in the member 34. Located around the inner periphery 59, see Figs. 21 to 23 inclusive, of the notched member 52 is a split ring friction member 60, the open ends of which are provided with upstanding pin members 61 which project up into the opening 62 in the slide member 44, shown in Fig. 20. The inner sides of the opening 62 comprise cam surfaces 63. The split ring friction member 60 is maintained in an expanded position against the member 52 by means of the spring 64. Under these conditions, if the split ring member 60 is not otherwise acted upon, it will turn in the notched member 52 and the member 34 will not revolve when the member 52 turns; but if, the split ring member 60 is ex-

panded, the member 34 will become frictionally locked with the worm wheel 21 and will turn with it. By an inspection of Fig. 27 it will be noted that the dog member 55 is provided with a lower pin portion 65 which is adapted to engage in the curved open ends of the split ring 60. The dog member 55 is further provided with pawl portions 66; see Fig. 27, which are adapted to engage against the notched portions of member 52 when the dog member 55 is pivoted in the holes 57 and 58 in the member 48 and 34 respectively. This condition takes place when the worm wheel is turned from right to left unless the dog member 55 is acted upon from other apparatus to prevent it from pivoting from right to left. In other words, if the dog member 55 is maintained in the position shown in Fig. 21, the disc 48 will not lock up with the disc 34. If there is nothing to prevent the dog member 55 from pivoting to the right or left it will engage, by means of the pawls 66 with the notched member 52 thereby locking the worm wheel 21 with the member 34 and pinion 24.

As shown in Fig. 19, the disc 30 normally covers the slots 46 in the member 34 and until the disc 30 is rotated slightly no foreign matter can engage in these slots 46 which would cause the dog member 55 to pivot, but when the disc 30 is interrupted or retarded in rotation the following takes place. The cam slot 42 causes the slide 44 to move to the left, as viewed in Fig. 20, and as the cam sides 63 of the slide move convergingly they contact the open ends of the split friction ring 60 permitting it to rotate freely in the notched member 52; therefore the pins 61 do not engage the dog member 55, with the result that the dog 55 does not pivot and engage one of its pawl portions 66 with the notched member 52.

In other words, whenever the unit, as disclosed in Figs. 18 to 27 inclusive, are in a position with the slots 31 and 46 in register, the adjacent pinion 24 is directly engaged with the worm wheel 21 and will rotate in the same direction that the worm wheel is turned by the motor 17. If the motor 17 is reversed, the dog 55 will reverse and the pinion 24 will reverse; however, if the dog 55 is maintained in a neutral position, as shown in Fig. 21, and the slide 44 is over to the left, the worm wheel 21 may rotate and the pinion 24 will not be engaged.

As before stated, the opposite side of the unit disclosed in Figs. 18 to 27 is exactly the same and operates in the same manner. The control of this unit depends entirely on the outside interference with the disc 30 which is the same in operation from either side of the unit and this is controlled from one rod or shaft 70 mounted on the upper portion of the automobile door. When the shaft 70 is raised or lowered, the side of the unit illustrated in Figs. 19 to 25 is affected and operates the window sash; and when the shaft 70 is rotated the other side of the unit, not specifically described, is contacted and made to operate the ventilator, as will now be described.

I will first describe the mechanism and operation of the apparatus concerned with the raising and lowering of the window sash 11. Located in the unit 13 between the side portions 22 and 23 is a unit 75 and adjacent thereto is an electrical switch 76 the switch being pivoted in the unit 13 by means of the pin 77. This switch is operated by both the sash 11 and the ventilator 12. In the case of the ventilator, the central switch lever 78 pivots to the right or left, forward and reverse,

and the body of the switch is held in a neutral position, as shown in Fig. 6. When the switch 76 is operated by the window pane 11, the reverse is true; the switch lever 78 is held in a neutral position as shown in Fig. 6, and the body of the switch is pivoted to the right or left, forward and reverse. Further along in the description, the details of the inside of the switch will be described.

On the side of the unit 75 I have provided a vertical slide member 79 which is provided with an attached block member 80 which projects through the opening 81 provided therefor in the side 22 of the unit 13, see Fig. 3. The rod 70 is secured in the block such that when the rod 70 is raised or lowered the slide 79 will respond likewise. Also located in the slide 79 are recessed cam tracks 82 and 83. Engaging the cam track is a horizontal sliding dog lever 84. It will be apparent that when the slide 79 is raised or lowered from the neutral position shown in Fig. 6, the dog slide member 84 will be slid to the left-hand side. As shown in Fig. 6, the dog slide 84 is in the right-hand position being normally maintained thereby by means of the spring 85. In this position the dog end of the slide 84 is engaged with the clutch unit previously described. In this position, as shown in Fig. 6, the end of the dog has entered one of the slots 31 of the disc 30 thereby stopping its further rotation; and as the member 34 continues to rotate, one of its slots 46 rides under the end of the dog slide 84 at which time the dog slide advances into the slot 46 thereby bringing the member 34 to rest. While this action has been taking place, it will be noted by an inspection of Fig. 6, that the disc 30 in its slight rotation on the pinion 24 has caused the slide pin 43 to cam outwardly in the cam slot; therefore the slide member 44 is thrown to the left from the position shown in Fig. 20 and the dog member 55, which previously was tipped and engaged with the notched member 52, has been returned to a neutral position thereby disengaging the driving worm wheel 21 from the pinion 24.

Attached to the switch body 76 is a lever 87 which is pivotally and slidably engaged with the vertical slide member 79 such that when the slide 79 is raised or lowered, the switch body 76 will pivot on the pin 77 thereby operating the motor in a forward or reverse direction. If it is now assumed that the rod 70 is either raised or lowered, it will be apparent that the slide dog member 84 will be withdrawn from the clutch unit, in which event the disc 30 will snap back to the position shown in Fig. 19. Consequently, the slide member 44 returns to the position shown in Fig. 20 thereby permitting the split friction ring 60 to engage the notched member 52 which is directly connected with the worm wheel 21 and thereby causing the dog 55 to engage with said notched member and, as previously pointed out, engaging the pinion 24. The pinion 24 will now revolve either clockwise or counter-clockwise, the direction depending upon which way the switch 76 is tipped by means of the lever 87.

By an inspection of Fig. 3 it will be observed that the pinion 24 is directly engaged with the rack 14 which is connected with the window sash 11; therefore, when the pinion 24 rotates, the rack moves in a vertical direction, either up or down.

In order that the mechanism will not be damaged, jammed or otherwise displaced when the window 11 has been opened or closed to its full limit by a careless operator who does not release the control mechanism in time, I have provided

an automatic mechanical cut-out attachment which will act at the proper time to operate the slide 79 and neutralize the switch 76 thereby discontinuing the course of power. I have attained these ends in the following manner as I will now describe: Attached to the outside of the unit 13 is a pivoted bell-crank lever 90 having a horizontal arm 91 which is provided with an elongated slot 92, better shown in Fig. 3, in which is slidably engaged a pin 93 the fixed end of which is attached to the block 80 located on the slide 79. On the perpendicular end of the bell-crank lever 90 I have provided a pivoted roll member 94. It will thus be apparent that when the bell-crank lever 90 is oscillated, the slide member 79 will be pushed up or down thereby tilting the body portion of the switch 76 and thereby stopping the electric motor 17. To effect this result, I have placed at the proper position, a cam member 95 on the lower portion of the rack 14 such that when the rack and window 11 reach a position approximating the closed position, the cam 95 will move the slide 79 to a neutral position. In a similar manner, I have placed a second cam member 96, Fig. 5, on upper end of the rack 14 so that when the window is being dropped, or opened, the cam 96 will engage the roll 94 and throw the bell-crank lever 90 in the opposite direction thereby returning the switch body portion to a neutral position.

With special reference to Fig. 5, I have shown an elongated slot 97 through which operates a bolt connected with the window sash 11. The elongated slot 97 allows a small amount of backlash so that the motor has a chance to assume its full load by the time the rack 14 actually starts to operate the window 11. Under normal conditions this is not necessary but under freezing conditions when the window 11 may possibly be stuck with frost or light ice it is a great advantage, as the sudden force being applied quickly starts the window moving when otherwise the motor might not have built up enough force to effect this result. It will thus be seen that by raising or lowering the rod 70 the window 11 may be raised or lowered, as the case may be, and automatically stopped at the end of its travel, also that the window will automatically come to a stop at any time pressure is released from the rod 70 thereby allowing the slide 79 to return to the neutral position shown in Fig. 6.

When it is desired to operate the ventilator 12, the rod 70 is oscillated to the right or left. By an inspection of Fig. 3, it will be observed that the lower end of the rod 70 which continues into the block 80 is threaded so that the rod 70 may turn or pivot from side to side in the block 80, but when moved up or down the block 80 will also move up or down, but when the rod 70 is pivoted in the block 80 there is no effect on said block. Above the block 80 I have provided a bracket 98 through which the square portion of the rod 70 passes, and in said bracket is located a segmental gear 99 the toothed side of which engages through an opening 100 provided in the side 22 of the unit 13. In the unit 75 is a vertical shaft 101 on which is secured the plate 102 which is provided with pins 103 adapted to engage the teeth of the segment 99. It will thus be apparent that when the rod 70 is oscillated, the plate 102 will likewise oscillate. Secured to shaft 101, Fig. 8, is a cam member 104 which operates a lever 105 which is pivoted at 106. By an inspection of Fig. 8, it will be apparent that when the cam 104 oscillates to the right or left

the lever 105 will swing on the pivot 106. The free end 107 of the lever 105 comprises a ball and socket connection with a horizontally located sliding dog member 108 similar to member 84. This slide dog member 108 is engageable with the left-hand side of the unit shown in Fig. 18, the details of which are identical with the right-hand side previously described. It will thus be apparent that the clutch apparatus concerned in the unit shown in Fig. 18 will operate in the same manner and be controlled in the same manner by the lever 108 as was the case in connection with lever 84. The spring 109 normally holds the lever 108 to the right-hand side, as viewed in Fig. 8, in a like manner to the spring 85 in connection with lever 84; therefore, it will be apparent that when the dog lever 108 is withdrawn from its position shown in Fig. 8, the worm wheel 21 becomes frictionally engaged with the pinion 26 on the far side of the unit 13, as viewed from Fig. 3, and the rack 25 will be caused to move in a horizontal direction to the right or left, as the case may be. The direction of the motor drive of the worm wheel 21 is controlled by means of the resilient lever 110 which is pivoted at 111 to the cam 104, the other end of which is pivoted to the upper end of the switch lever 78. In this case, when the rod 70 is swung or pivoted to the right or left, the body portion of the switch 76 is in a neutral position, as shown in Fig. 6, and the lever 78 moves in the body of the switch thereby making the electrical connections with the motor 17 to start, stop, and reverse same.

In connection with the ventilator mechanism, I have provided an automatic mechanical cut-out to stop the apparatus when the ventilator has reached its limit of movements as will now be described. Located under the top of the casing of the unit 13 is a slide member 112 which is provided with stop members 115 and 116 extending upwardly through slots 115a and 116a respectively in the top of the casing of unit 13. Springs 115b and 116b respectively hold the slide in a normal position. Located on an extension portion 25a of the rack 25 is a stop member 117 which engages the stop members 115 and 116 when the rack 25 reaches its limit of travel either to the right or to the left. In Fig. 10, I have shown a plan view of the extreme left end of the slide 112 in which is shown an open area 118. On the upper side of the plate 102 fixed to the shaft 101 is located a vertically positioned pin 119 which projects upwardly through the area 118 in the slide 112 and through an opening 120 provided in the top side of the unit 13. This area 118 is outlined by the cam surfaces 121 and 122 and end portions 123 and 124. The pin 119 operates in this area 118 and is so located that when the rack stop member 117 contacts with the slide stop member 115, the end portion 124 engages the pin 119 and turns the rod 70 to a neutral position thereby stopping the movement of the ventilator, and in a similar manner, when the rack stop member 117 moves in the reverse direction to the end of its normal travel it engages the slide stop member 116 and thereby pulls the slide 112 to the right contacting the end 123 of the opening 118 reversing the rotation of the rod 70 and again returning the connected mechanism to a neutral position.

Figs. 28 to 31 inclusive disclose a simple switch fixture from which the rod 70 is operated and comprises the following: 130 comprises the frame of the apparatus which is directly attached to the structure of the automobile door. Right-angled

brackets 131 and 132 are secured to the frame 130, as shown in Fig. 31, and another member 133 is also secured to the frame 130 at ninety degrees thereto. The member 133 is provided with a horizontal slot 134 at its rear portion through which is slidably located a pin or finger control lever 135. The pin 135 is pivotally fixed in a universal knuckle member 136 to which is attached a shaft 70a which is a continuation of the previously referred to shaft 70. In the face of the frame 130 are located four slots 140 each of which are located at ninety degrees to each other. These slots 140 are adapted to receive the finger lever or pin 135 which is pivotally mounted in the universal knuckle member 136. It will be apparent from an inspection of the drawings that when the finger member 135 is moved up or down, or from left to right, the rod 70 will move likewise and therefore produce the results in the unit 13 as heretofore described and illustrated in the drawings.

Referring to Fig. 2, I have provided an auxiliary crowding device to the rack 25 for the purpose of seating the ventilator tightly in place to eliminate all possibility of draft through such a closure. In Fig. 2, it will be noted that at 150 I have provided a cam member attached to the rack member 25a which engages with a similar slideable cam member 151 such that due to the spring 152 the slide 151 will slightly crowd the rack 25 and maintain a force to the right-hand side after the rack has been stopped by means of the slide 112. In other words the cam faces on the members 150 and 151 maintain a pressure against the rack, gears etc. up to the ventilator 12 after the mechanism is electrically disconnected thereby holding the ventilator window 12 in a tightly closed position until further operated upon by the apparatus located in the unit 13.

It is also true that the main drive, clutch apparatus and switching mechanism cannot operate except when the lever 135 is moved and it is impossible for this lever to be operated in more than one position at a time.

Figures 11 to 17 inclusive indicate the details of the switch 76, in the position shown in Fig. 12, the electrical current is off; in other words the switch is in a neutral position; the contacts are numbered to correspond with the circuit diagram shown in Fig. 32. When the rod member 70 is rotated to the left or right-hand side the switch member 78 is pivoted accordingly on the pin 77 and the electric motor 17 is energized either forward or reverse, as the case may be, and due to the fact that the clutch portion which operates the pinion 26 and rack 25 the ventilator is operated.

When the switch member is in the neutral position shown in Fig. 12, and the rod 70 is pushed up or down, the body portion 76 of the switch pivots on the pin 77 and the motor is again energized right or left-hand, as the case may be. In this action the clutch member 84 is withdrawn releasing the clutch pinion 24 which raises or lowers the window sash rack member 14. In this position, the clutch member 108 is engaging the clutch thereby locking the pinion 26.

Having thus described my invention, what I claim as new is:

1. An improved automobile door mechanism comprising, a door frame having a sliding sash and a swinging ventilator, an electrically operated driving unit mounted in said door comprising a casing, a reversible electric motor mounted in said casing, said motor being connected with

a multiple clutch mounted in said casing, said multiple clutch having a central drive member and a frictionally engaged pinion located on each side of the drive member, a rack and pinion member connecting said sash with one of said pinions, a rack and pinion and geared driving rod connected with said swinging ventilator and the other of said pinions, a switch lever member mounted in said casing and door, means comprising a cam and slide member located in said casing and connecting with said lever and said clutch for the purpose of locking the pinion connected with said sash rack, another locking means located in said switch casing comprising a second cam and connecting lever engaging with a slide member located in said casing and connecting said lever with said clutch for locking the second said pinion and connecting mechanism to said ventilator, means for engaging said motor in a reversible manner with said clutch comprising a pivoted switch member connected with said switch lever and in circuit with said motor.

2. An improved automobile door mechanism comprising a door frame having a sliding sash and swinging ventilator, an electrically operated driving unit mounted in said door, said unit comprising a reversible electric motor mounted in said door and being connected with a reversible multiple clutch mounted in said unit, said clutch having a central drive member connected with said motor and frictionally engaged with pinion members located on either side of said central drive member for the purpose of operating said sliding sash and swinging ventilator, a rack engaging one of said pinions and a geared driving rod connecting with said swinging ventilator, a second rack engaging with the other pinion for the purpose of operating said sliding sash, a switch lever member mounted on said unit, means comprising a cam and slide member located in said casing connecting said switch lever with said clutch for the purpose of locking one of said pinions and connecting mechanism leading to said ventilator, means for engaging said motor in a reversible manner with said clutch comprising a pivoted switch member connected with said switch lever and in circuit with said motor.

3. An improved automobile door mechanism comprising a door frame having a sliding sash and swinging ventilator mounted therein, an electrically operated driving unit mounted in said door and connecting with said sash and ventilator, the said unit comprising a reversible electric motor located in said unit and being connected with a reversible multiple clutch unit, said clutch having a middle drive member connected with said motor and a frictionally driven pinion located on each side of the said middle drive member, a horizontal rack engaging one of said pinions and a geared driving rod member connected with said ventilator, a vertical rack member engaging the other of said pinions and connected with said sliding sash, a switch lever member mounted in said door and connecting with a cam and slide lever, said slide lever engaging with a portion of said clutch for the pur-

pose of locking one of said pinions connecting with said ventilator and with said middle drive member, a cam and lever engaging said switch lever with a second slide member engaging with 5 said clutch member for the purpose of locking the other pinion member connecting with said sliding sash and with said middle drive member, means for engaging said motor in a reversible manner with said clutch comprising a pivoted switch member connected with said switch member and in circuit with said motor.

4. An improved automobile door mechanism comprising a door frame having a sliding sash and swinging ventilator mounted therein, an electrically operated driving unit mounted in said door and connected with said sash and ventilator, the said unit comprising a reversible electric motor directly connected with a reversible multiple clutch also mounted in said unit, the said clutch comprising a middle drive member frictionally engaged with pinion and rack members located on opposite sides of the said middle drive portion, one of said racks engaging with said sliding sash and cam and lever members connecting with said clutch for the purpose of locking or unlocking one of said pinions with one of said racks the connecting member between said clutch and said cam being a common switch lever located in said door, the other said rack being geared to a drive rod connected with said ventilator and the other of said pinions, a cam, lever and slide member engaging with said clutch on the opposite side of said middle drive member and with said switch lever for the purpose of locking said second pinion with said middle drive member, a pivoted switch connected with said switch lever and in circuit with said motor and operated by said switch lever.

5. An improved automobile door mechanism comprising a door frame having a sliding sash and swinging ventilator mounted therein, an electrically operated driving unit mounted in said door and connected with said sash and ventilator, the said unit comprising a reversible electric motor directly geared to a middle drive member mounted in a multiple clutch and having a frictionally engageable pinion located on each side of said middle drive member, dog members located in said clutch on each side of said middle drive member for the purpose of locking said pinions with said middle drive member, sliding levers located in said unit adapted to engage each side of said clutch for the purpose of pivoting said dog members and releasing said pinions 45 from said middle drive member, a switch lever connected with a pivoted switch which is connected in circuit with said motor, said switch lever connected with cam and slide members 50 engaging said clutch for the purpose of releasing one of said pinions from said middle drive member, said switch lever also connected with a cam, lever and slide member adapted to engage with said clutch and release the other said pinion from said middle drive member, a rack member 55 engaging said sash and one of said pinions, a second rack member engaging a geared drive rod connecting with said ventilator.

DANIEL L. CHANDLER.
